GORHAM MANUFACTURING COMPANY, INCORPORATED, OF PROVI-
DENCE, RHODE ISLAND.

ELECTRIC CANDELABRUM.

SPECIFICATION forming part of Letters Patent No. 783,787, dated February 28, 1905.

Application filed June 30, 1903. Serial No. 163,728.

To all whom it may concern:

Be it known that I, CHARLES E. WEEKS, a citizen of the United States, residing at Providence, in the county of Providence and State 5 of Rhode Island, have invented a new and useful Improvement in Electric Candelabra, of which the following is a specification.

This invention has reference to an improvement in electric candelabra, and more particularly to an improvement in the supporting-tube for the lamp-socket of an electric candelabrum.

In electric candelabra as heretofore constructed the supporting-tube extending upward in the candelabrum has two oppositely-disposed transverse apertures near its upper end. The lamp-socket is secured by screwing it into the upper end of the supporting-tube, and the lamp-wires extend upward in the tube. In wiring it is required to bring the wires through the apertures in the tube and secure them to the terminals of the lamp-socket. In practice it has been found that this construction is detrimental, as it requires time and skill for the electrician to bring the wires from the inside of the tube through the apertures to the outside of the tube to secure them to the lamp-socket.

The object of my invention is to facilitate the operation of wiring an electric candelabrum, and I accomplish this object by slitting the upper end of the tube downward to form two oppositely-disposed slots having the form of an inverted keyhole and reinforcing the end 35 by a sleeve on the outside of the tube, the apertures for the wires being formed by the lower ends of the slots not covered by the sleeve.

My invention consists in the peculiar and novel construction of a lamp-socket-supporting tube for electric candelabra, having two oppositely-disposed slots extending downward from the top of the tube and a reinforcing-sleeve on the end of the tube to partly cover the slots and strengthen the end of the 45 tube, as will be more fully set forth herein-after.

Figure 1 is a sectional view in elevation of an electric candelabrum, showing my im-

proved construction of the supporting-tube to facilitate the wiring from the interior of the tube to the terminals of the lamp-socket. Fig. 2 is a side view of the lamp-socket-supporting tube removed from the candelabrum, and Fig. 3 is a sectional view taken lengthwise through the supporting-tube and the reinforcing-sleeve.

In the drawings, *a* represents an electric lamp; *b*, the lamp-socket; *c*, the socket-supporting tube; *d*, the ornamental fitting; *ee*, the wires, and *f*, a cylindrical shell of glass or celluloid, representing the candle of an electric candelabrum. The lamp *a* screws into the socket *b* to connect with the terminals *b'* *b''* in the usual way. The socket *b* has the lower screw-threaded end *b'* in screw-thread engagement with the interior of the upper end of the supporting-tube *c*. In the supporting-tube *c* are the two oppositely-disposed slots *c'c'*, having the shape of an inverted key-hole extending from the upper end of the tube 70 downward, and over this end of the tube is placed the reinforcing-sleeve *c''* to partly close the slots *c'c''* and strengthen the end of the tube. The supporting-tube *c* has the enlarged lower end *c''* in screw-thread engagement 75 with the upwardly-extending cylindrical boss *d'*, forming a part of the fitting *d*, and the shell *f*, representing a candle, has the contracted upper end *f'* resting on the lamp-socket *b*.

In assembling and wiring the electric candelabrum the supporting-tube *c* is screwed onto the boss *d'* of the fitting *d*, the wires *ee* are carried upward through the supporting-tube and bent outward through the slots *c'c'*, the reinforcing-sleeve *c''* is brought downward 85 over the upper end to partly cover the slots *c'c''* and strengthen the end of the tube, the lamp-socket *b* is secured into the upper end of the supporting-tube and the ends of the wires *ee* are screwed to the socket-terminals *b'* *b''*, the cylindrical shell *f* is carried downward over the socket *b* and the supporting-tube *c* into the ornamental fitting *d* and is held in position by the contracted end *f'* resting on the socket *b*, and the lamp *a* is secured 95 in the socket *b* in the usual way.

By the use of my improved supporting-tube less time and skill are required in wiring, and a more perfect electric candelabrum is constructed than has heretofore been done.

5 Having thus described my invention, I claim as new and desire to secure by Letters Patent—

In an electric candelabrum, the combination of the lamp *a*, the socket *b* having the terminals *b'* *b''* and the lower screw-threaded end *b'*
10 in screw-thread engagement with the interior of the upper end of the supporting-tube, the supporting-tube *c* having the two oppositely-disposed slots *c'* *c''* extending downward from its upper end, the reinforcing-sleeve *c'* and
15 the enlarged lower end *c''* in screw-thread en-

gagement with the boss *d'* forming a part of the ornamental fitting *d*, the wires *e e* in the supporting-tube extending outward through the slots *c'* *c''* and secured to the terminals *b'* *b''*, and the cylindrical shell *f* with the contracted upper end *f'* representing a candle, all for the purpose as described. 20

In testimony whereof I have signed my name to this specification in the presence of two subscribing witnesses.

CHARLES E. WEEKS.
